METHOD OF MAKING BOXES

Ernest G. Rider, Philadelphia, Pa., assignor to
 Stokes and Smith Company, Philadelphia, Pa.,
 a corporation of Pennsylvania

Application March 12, 1937, Serial No. 130,435

16 Claims. (Cl. 93—54)

My invention relates to the construction of boxes, box lids, containers and the like, generically termed "boxes," and particularly to paper board and like boxes which are reinforced or stayed by sheet material, more particularly in the form of tabs, of paper or equivalent.

In accordance with my invention, tab material, prior to its application to box structure, is rendered plastic, limp or flaccid, and substantially 10 wholly free of stiffness and resilience, by moistening it, as subjecting it to the action of water, wet steam, or other suitable liquid or vapor, and while in the resultant plastic or moldable state, is adhesively applied to overlie and reinforce 15 corners and, in some instances, upper edges of a box; specifically, in making boxes of unusual strength, the tab material is of such thickness that, except for the aforesaid pre-application treatment, it would be impractical or impossible 20 to utilize it for tabbing purposes.

Also in accordance with my invention, tab strip applied to each end wall of a box is of width sufficient to cover the end wall, to overlie the dihedral corner formed by the junction of the 25 end wall of the box bottom, and to embrace the top edge of the end wall; preferably the tab strip is of unusual thickness and is reduced to suitable state of plasticity or workability, prior to its application to the box structure, by subjecting it to 30 the softening action of moisture.

My invention further resides in the novel features hereinafter described and claimed.

For an understanding of my invention, reference is to be had to the accompanying drawings 35 in which:

Fig. 1, in perspective, schematically illustrates an arrangement for moistening tabs and applying them to box wrappers;

Fig. 1a, in perspective, shows a modified form 40 of tab-moistening apparatus;

Figs. 2-4 illustrate successive steps of application of a tabbed wrapper to box structure; and Fig. 5, in perspective, illustrates the completed 45 box;

Fig. 6, in perspective, illustrates an arrangement conveying coated tabs;

Figs. 7-10 illustrate successive steps of application 50 of the tabs of Fig. 6 to box structure; and

Fig. 11, in perspective, illustrates the completed box;

Fig. 12, in perspective, illustrates a wrapper having thereon tab strips adapted to cover the ends of a box;

Figs. 13-14 illustrate successive steps of appli- 55

cation of the wrapper of Fig. 12 to a box; and Fig. 15 illustrates the completed box;

Fig. 16 illustrates a tabbed wrapper which is a modification of the wrapper of Fig. 12;

Fig. 17 discloses the wrapper of Fig. 16 partially applied; and Fig. 18 illustrates the completed box.

Referring to Fig. 1, wrappers W are removed in succession from the stack WS on table 1, and fed into engagement with the adhesive-applying 10 roll 2 from which they are diverted by the blades 3 onto a conveyor 4 which transports the freshly coated wrappers toward a wrapper-applying station, or wrapping machine, such as shown, for example, in Federwitz Patent #2,044,606. 15

Preferably, the conveyor belt 4 passes over a housing H whose upper wall is perforated and whose interior is connected, as by conduit N, to an air pump or other source of suction.

Each of the wrappers W, for purpose of explanation, is considered to be divided, by lines X, Y and Z, which may be non-existent on the actual wrapper, into: a bottom panel b whose length and width correspond to the length and width of the bottom of the box to which the 20 wrapper is to be applied; a pair of end panels e, and a pair of side panels s. Each of the side panels s extends beyond the lines Y to form flaps f, which, as hereinafter described, are bent into engagement with the end walls of the box. The 25 width of each of the end and side panels is greater than the height of the box to which the 30 wrapper is to be applied by the width of the marginal strip m beyond the line Z on each of 35 these panels.

Prior to application of a wrapper W to a box, there is attached to each side panel of each wrapper a pair of tabs T; each tab, disposed in part to overlie one of the flaps f and the adjacent part of the side panel s, is of such length as to 40 project beyond the line Z and overlie part of the margin m.

Preferably, as indicated in Fig. 1, the tabs are applied to the wrapper substantially concurrently with coating of the wrapper with adhesive by 45 mechanism generally of the type illustrated and claimed in Rider U. S. Patent #1,857,260. Briefly, concurrently with feeding of a wrapper from the stack WS to the glue roll 2, strips TS of un-gummed tabbing material are fed from the rolls 50 TR; the ends of the strips are severed by the intermittently operated pairs of knives 5 to provide successive pairs of tabs T which are coated with adhesive by engagement with the transfer roll 6 from which they are diverted by strippers 55

1 onto the surface of the wrapper-coating roll 2; thus, the tabs are coated on both sides with adhesive, and they are, by roll 2, deposited on the wrapper in their proper positions. The agitating 5 roll 8 continuously revolving in the body of glue within the reservoir 9 maintains a coating of adhesive upon the periphery of the tab transfer roll 6. A suitable pump, not herein disclosed, may maintain a fountain of adhesive between 10 the wrapper-coating roll 2 and the doctor-roll 10.

15 In accordance with the present invention, as the tab strips are removed from the rolls TR, they pass over the rolls M, preferably consisting of, or faced with, felt, or other moisture-retaining material, to absorb sufficient moisture to render the tab strips limp or flaccid to desired or suitable extent.

20 The rolls M which may be continuously or intermittently rotated dip below the surface of water or other liquid in the reservoirs 11 continuously to maintain a plenum of moisture for transfer to the tab strips. The period during which any given portion of a strip TS remains in contact with the moisture-transferring surface 25 of the rolls M is preferably adjustable; specifically, the angular distance between the idler rolls 12 and 13 may be adjusted to vary the proportion of the total periphery of the moistener roll which is engaged by the tab strip. Thus, 30 the amount of moisture absorbed by the tabbing material may be varied to suit the particular material, or to obtain the desired plasticity.

35 Moistening the tabs suppresses their tendency to separate from the wrapper as the latter is bent more or less sharply incident to its diversion by the stripper blades 3 from the adhesive-applying roll 2. Other advantages will appear in the discussion of application of the tabbed wrapper to a box.

40 In making a box, the bottom panel B of a box blank is registered upon the panel b of the wrapper, and the assembly thus formed may then be placed upon the form-block F of a wrapping machine, such as shown in the aforesaid Federwitz patent, which will perform the steps hereinafter described, or such steps may be performed manually. The side panels s of the wrapper are then wiped into engagement with the corresponding side panels of the box blank, generally 50 as shown in Fig. 2, with the flaps f of the wrapper side panels projecting beyond the ends of the box, and the margins m of the side panels extending above the top edge of the box. Each 55 of the tabs T, as shown in Fig. 2, is, in part, in adhesive engagement with the side of the box, extends, in part, above the top edge of the side s of the box, and in part, projects beyond the end wall E of the box.

60 The next operation involves swinging of the flaps f of the side panels of the wrapper into engagement with the box end walls, Fig. 3. This operation, in a wrapping machine, is performed by folding tools 14; one pair of which is shown in Fig. 3. These tools are ordinarily yieldable or flexible to procure a wiping action affording 65 intimate engagement of the flaps and the box ends E. It has not heretofore been practical to use heavy tabs, for example, of thickness in excess of .005", because the stiffness of the tabs 70 precluded proper operation of the folding tools and, in particular, prevented the tabs from being folded sharply about the corners formed by the side and end walls; moreover, the resiliency of the tab material caused the tabs to tend to separate from the box end before the adhesive set. 75

When, with heavy tabs, it was attempted to increase the pressure of the side folding tools to extent sufficient to weaken the fibres of the tab material, the result was marring of the wrapper at the corner of the box.

5 By moistening the tabs, as above described, or in any other suitable manner, so that the tab material is limp at this wrapping stage, these difficulties are overcome and without sacrifice of strength of the completed box; in fact, it is possible to use tab material much heavier than previously employed, for example, of the order of .010" or .012" or more, thus to obtain an extremely strong box which, moreover, may be made with known types of machines. The tab 15 strip may be any suitable paper, for example, kraft, manila, rope stock, or any strong paper is preferable.

20 Subsequent to turn-in of the flaps f, the end panels e of the wrapper are wiped up into adhesive engagement with the box ends and the previously applied flaps f. Assuming the box is being wrapped by a machine of the aforesaid Federwitz patent, the next operation involves 25 turning of the marginal portions m of the wrapper panels, extending above the top edges of the box, downwardly and into engagement with the inside of the box; to that end the upper section UF of the form-block F is separated from the lower section LF, Fig. 4, and while the form 30 block is so separated, two pairs of turn-in tools 15, one for each vertical wall of the box, move inwardly to swing the marginal portions of the wrapper panels through an angle of approximately 90°, wiping them over the top edges of 35 the box, Fig. 4. After the margins of the wrapper panels and the tabs are turned in, the upper form UF is allowed sharply to descend, to wipe the turned-in marginal portions downwardly into engagement with the inside wall of the box, 40 Fig. 5.

When it was attempted to use heavy tab material in dry state, the tabs offered such resistance to bending by the tools 15 that the side or end walls of the box would flex and come into 45 the path of the upper form UF, so that when the latter descended, it would crush the flexed wall, or walls, of the box; in other instances, the stiffness of the turned over horizontal portions of the tabs was so great as to prevent the upper 50 form block UF from descending and nesting within the portion of the box extending beyond the lower form block LF, and when steps were taken to increase this pressure to extent sufficient to insure descent of form UF, the usual 55 attendant result was that the box walls were deformed.

60 All of these difficulties are overcome by moistening of the tab to extent making it plastic or limp during the period required to perform the various wrapping operations. When the applied tab dries it regains its former strength and stiffens without tendency to return to its original shape, thus affording great strength to the box at its tabbed corners and edges.

65 When the tabs are of thickness substantially in excess of .005", for example, of the order of .010" or .012", a box so constructed is of unusual strength not previously attainable. Manufacture of such box, because of moistening of the 70 tab strips to render them plastic, can be effected at high speed and with known machines.

75 In the arrangement shown in Fig. 1, moistening of the tabs or tab strips is effected by contact with a moistening roll; this same end may be ac-

complished in various other ways, for example, as indicated in Fig. 1a, the tab strips TS, in their movement toward the knives 5, may pass through a housing 16 to which hot moist steam may be supplied as by the pipe 17 from any suitable source, for example, the heating tray, not shown, for the glue reservoir 9 of Fig. 1; or the tab rolls TR may themselves be disposed in such a moistening chamber, or a humidor, either while in use or before use, for such period the strip is plastic or limp. When the tab strip, in the roll, is of a type having adhesive on one face, the latter expedients are not practical, and it is necessary to moisten the tabs or tab strip subsequent to removal from the roll; the strip must be moistened not only sufficiently to activate the adhesive thereon, but also to such extent suitably to reduce the stiffness or resilience of the strip.

It is not essential the entire tab be moistened; it is sufficient if it be suitably moistened in those areas where it is to be bent and particularly in that area which is to be turned over the top edge of a box wall. By stencilling the tab with moist pads in proper positions, it may be rendered plastic only at the necessary area or areas.

As indicated in Figs. 6 to 11, unwrapped boxes may be formed by applying a box blank BB to a pair of tabs LT, LT, each of length suitably greater than the total width of the box blank, i. e., greater than the sum of the widths of the side panels S, and the bottom panel B. Therefore, when the box walls are moved into box forming position, Fig. 7, the ends of the tabs project above the sides of the partially formed box. The central portion c of each tab overlies and reinforces the bottom edge of the box formed by the junction of the bottom panel B and an end panel E. The two vertical portions of each tab when folded, as shown in Fig. 8, overlie and reinforce the vertical corners of the box; this operation may be performed as by wrapping tools 14, Fig. 3, which produce gusset folds g in each tab at the bottom corners of the corresponding box end. The central portion c of the tab which extends beyond the box bottom is then wiped up into engagement with the box end, Fig. 9. Subsequently, turn-in tools, such as tools 15, Fig. 4, bend the marginal portions m of the tabs horizontally over the top edges of the box walls at the box corners, Fig. 10, and finally the inwardly turned portions m of the tabs are wiped downwardly into engagement with the inside of the box as by descent of the upper form block UF, Fig. 4.

By moistening the tabs, in any of the various modes specifically described, or in any other suitable manner, tab material of substantial thickness, for example, in excess of .005", may be used, affording an inexpensive box of unusual strength.

In manufacture of a box of this type having no wrapper to assist in holding the tab against the box, as during setting of the adhesive on the tab, moistening of the tabs is a decided advantage for tab strip thinner than about .005" and is essential for heavier tabs.

The tabbing material is usually procurable in rolls, as shown in Fig. 1; consequently, the tendency of the tab strip to curl is increased with decrease in diameter of the rolls. This tendency previously gave rise to many difficulties, including improper positioning of the tabs on the wrappers, failure of the tabs to be transported to the wrappers, and separation of the tabs from the

wrappers. To avoid these troubles, it was customary to discard the rolls before all of the tab material was used. By moistening the tabs, or the tabbing material, the curling tendency is overcome and the rolls TR may be used in their entirety without encountering any of these difficulties.

It shall be understood that while box-staying elements, as more particularly shown and described, may be and generally are so-called "tabs", nevertheless my invention contemplates any other form of the staying elements, including unitary or composite wrappers or labels; and it shall be understood that the workability or plasticity of the staying elements herein contemplated is such as not procured by the moisture component of the glue or other adhesive as heretofore in the art commonly constituted and applied, but that the extents of application of moisture hereby contemplated include those which procure a plasticity or workability of the staying elements which is substantially and significantly greater than that procurable by the moisture content of ordinarily and commonly used glue or adhesive.

Referring to Fig. 12, there are shown, adhesively applied to the wrapper W, two tabs TE, one at each end of the wrapper. Each of the tabs TE is of such width and so applied as entirely to cover that section of a wrapper end-panel e bounded by the lines y and z, to lap the bottom panel b of the wrapper, and to project beyond line z, at least in part to cover the margin m of panel e between line z and the edge of the panel. Furthermore, each of tabs TE is of such length and so applied as to extend across corner-notches K of the wrapper onto the side panels s, each end of each tab substantially covering a flap f of a side panel s, extending beyond line z to lap at least part of margin m of the side panel, and beyond line y to lap an end of that section of the side panel defined by lines x, y and z.

To make a box, an unstayed blank BB is placed upon the tabbed wrapper of Fig. 12 with its bottom panel B in registered, adhesive engagement with panel b of the wrapper, to form an assembly which may then be disposed on the form-block of a wrapping machine. The portions of tabs TE which lap the bottom panel b of the wrapper adhesively engage and extend across the ends of the bottom panel B of the box blank. The side panels s of the wrapper are then wiped into adhesive engagement with the side walls S of the box blank; subsequently, the flaps f of the side panels are swung, as by corner-lap tools 14, into adhesive engagement with the box ends E. The latter operation also bends the tabs TE to embrace the vertical corners of the box formed by the joinder of the side and end walls of the blank and peels portions g of the tabs TE from the wrapper end panels e, Fig. 13. Since the adhesive on the engaging surfaces of the panels e of the wrapper and tabs TE is still unset, this partial separation of tabs TE from panels e is accomplished without difficulty.

By the next folding operation, the panels e of the wrapper and the overlying sections of tabs TE are swung upwardly for application to the end walls E of the box. The central portion of each tab TE is thus applied to complete the covering of an end wall E, previously partially covered by those tab portions adherent to the flaps f. The triangular portions of each panel e not covered by tab TE, Fig. 13, adhesively engage and overlie the flaps f.

By the subsequent folding operation which may be performed by turn-in tools, such as 15, Fig. 14, the portions of the wrapper panels and of the tabs TE which project above the top edges of the box are turned inwardly, as shown in Fig. 14, over the top edges of the box and thereafter further folded downwardly into adhesive engagement with the inside of the box, as by descent of the upper form-block UF, to form the box shown in Fig. 15.

Each of tabs TE therefore completely covers an end of the box, reinforces the lower corner formed by junction of an end panel E with the bottom panel E of the box, reinforces the vertical corners formed by junction of the end panel E with the side panels S, reinforces the two trihedral corners at the junctions of the bottom, end and side panels of the box, embraces the top edge of the end panel, and embraces the top edges of the side and end panels where they join to form the upper corners of the box.

Preferably, the tabs TE are of heavy tab material having, for example, thickness of not less than about 0.005" and, for some purposes, as great as 0.01" or more. When made of such heavy material, the tabs, after, or before, they are cut from the rolls or continuous strip of tabbing material, are rendered pliable by subjection to moisture, as previously herein described, and while still pliable are applied to a box blank or to a wrapper applied, as above described, to a box blank.

The resulting box is of great strength; it is particularly suited for use as a box or box lid used to store articles, as shoes, ordinarily disposed endwise on shelves and pulled from place by persons who put their finger tips under the lid or over the top edge of the end of the lid or box.

When the tabbing at the end of the box is provided by tabs TE, there is produced at each lower corner of the box a gusset fold in the portions g of the tab (Fig. 13) which, particularly when the tab material is of the preferred thickness, produces a noticeable bulge which is for some uses of a box objectionable. This objection is overcome by using three tabs at each end of the box, Fig. 16, instead of a single long tab.

Referring to Fig. 16, each of the tabs ET may be considered equivalent to the central portion of a tab TE, Fig. 12, and each end pair of tabs ST, Fig. 16, may be considered equivalent to the ends of a tab TE of Fig. 12. As appears from Fig. 17, when the wrapper side panels s are applied to the box side walls S and the flaps f turned into engagement with the box ends E, the middle sections of the tabbing (unlike Fig. 13) are not in part peeled from the end walls. Consequently, when the end panels of the wrapper are folded upwardly, there are no gusset folds at the lower corners of the box ends.

The resulting box, Fig. 18, is similar to that of Fig. 15 using tabs TE, in that a continuous piece of tabbing material completely covers each end of the box, extends beyond the lower edge of the box into engagement with the box bottom, and extends over the top edge of the box end downwardly into adhesive engagement with the inside surface of the box end and in that the section of tabbing covering the box end is joined during formation of the box to sections of tabbing which overlie the vertical corners of the box and which pass over the top edges of the side and end walls at and near their junction and thence into adhesive engagement with the inside of the box.

The tabbing, whether of the single piece con-

struction of Fig. 12, or the three-piece construction of Fig. 16, is preferably of material heavier than previously considered feasible for tabbing purposes made plastic by subjection to water, steam, or the like, prior to being bent over edges 5 of a box blank.

Preferably the coating, tabbing and feeding of the wrappers is effected in accordance with the methods specifically described in connection with Fig. 1 and the tabbing may be rendered plastic in 10 any of the various ways herein described.

What I claim is:

1. The method of making a box which comprises subjecting ungummed sheet material to moisture to render it plastic, and, while the sheet material is plastic, adhesively applying it to a box blank to embrace the top edges of adjoining panels of the blank. 15

2. The method of making a box which comprises subjecting ungummed sheet material to moisture to render it plastic, and, while the sheet material is plastic, adhesively applying it to a wrapper to form a tabbed wrapper, and adhesively applying the tabbed wrapper to a box blank to form and wrap a box. 25

3. The method of making a box which comprises moistening an ungummed strip of tabbing material to render it limp, and, while the strip is limp, cutting tabs therefrom, and adhesively applying the tabs to a box blank to hold the 30 panels thereof in box-forming position.

4. The method of making a box which comprises moistening a strip of tabbing material to render it limp, coating the strip with adhesive, and, while the strip is limp and freshly coated 35 with adhesive, cutting tabs therefrom, adhesively applying the tabs to a wrapper to form a tabbed wrapper, and adhesively applying the tabbed wrapper to a box blank to form and wrap a box. 40

5. The method of making boxes which comprises intermittently feeding strips of tabbing material from rolls thereof, moistening the strips as fed from the rolls to render them limp, and, while the strips are limp, applying adhesive 45 thereto, cutting tabs therefrom, and adhesively applying the tabs to box blanks to embrace the top edges of adjoining panels of the blank.

6. The method of making a box which comprises moistening sheet tabbing material to render it plastic, thereafter coating the sheet material with adhesive, and, while the sheet material is plastic and the adhesive thereon unset, applying the tabbing material to hold panels of a box blank in box-forming position. 50

7. The method of making a box which comprises moistening tabbing material to render it plastic, coating the tabbing material with adhesive, coating a wrapper with adhesive, and, while the tabbing material is plastic and the adhesive on the wrapper and the tabbing material unset, applying the tabbing material and the wrapper simultaneously to stay and wrap a box. 60

8. The method of making a box which comprises moistening tabbing material to render it plastic, coating the tabbing material with adhesive, coating a wrapper with adhesive, and, while the tabbing material is plastic and the adhesive on the wrapper and the tabbing material unset, applying the tabbing material to the wrapper to form a tabbed wrapper, and applying the tabbed wrapper to an unstayed box simultaneously to wrap and stay the box. 65

9. The method of preparing a tabbed wrapper and applying it to an unstayed box which com- 75

prises in any sequence, the steps of coating a wrapper with adhesive, coating tabs with adhesive, moistening the tabs to render them plastic, applying the tabs to the wrapper, and thereafter, before setting of any of the adhesive and while the tabs are plastic, applying the wrapper and tabs to an unstayed box simultaneously to wrap and stay the box.

10. The method of forming boxes which comprises coating wrappers with adhesive and feeding them along a path toward a box-wrapping station, at a point in said path, applying tabs to the coated wrappers, moistening the tabs prior to their application to wrappers to render them plastic, and, at said station while the tabs are plastic and before setting of the adhesive coatings of the wrappers, applying the tabs and wrappers to unstayed box blanks simultaneously to wrap and stay boxes.

20. 11. The method of making a box which comprises subjecting unguammed sheet material to moisture to render it plastic, and, while the sheet material is plastic, adhesively applying it entirely to cover one face of an end of the box, to pass over the top edge of said end of the box and into engagement with the other face of said end of the box, and in part to cover the bottom of the box.

12. The method of making a box which comprises subjecting tab strips to moisture to render them plastic, thereafter coating the strips with adhesive, and while the tab strips are still plastic and the adhesive thereon unset, applying the strips entirely to cover the exterior faces of the ends of the box, to pass over the top edges of the box ends and into engagement with the inner faces of the box ends, and in part to cover the box bottom.

13. The method of making a box which com-

prises subjecting elongated unguammed tabs to moisture to render them plastic, and, while the strips are plastic, adhesively applying them to overlie the horizontal and vertical corners at the ends of the box, and to embrace the top edges 5 of the side and end panels of the box.

14. The method of making a box which comprises subjecting elongated, wide tab strips to moisture to render them plastic, coating the strips with adhesive, and while the tab strips 10 are still plastic, adhesively applying them entirely to cover the exterior faces of the ends of the box, to pass over the top edges of the box ends into adhesive engagement with the inner faces of the box ends, and in part to cover the 15 bottom and sides of the box.

15. In the art of staying box elements to each other, a method which comprises moistening a sheet of staying material, of substantial stiffness and resilience and having a thickness in excess 20 of five thousandths of an inch, to render it plastic and substantially wholly free of stiffness and resilience, and, while the sheet material is plastic and substantially wholly free of stiffness and resilience, adhesively applying it to adjoining 25 box elements.

16. In the art of staying box elements to each other, a method which comprises moistening a sheet of staying material, of substantial stiffness and resilience and having a thickness in excess 30 of five thousandths of an inch, to render it plastic and substantially wholly free of stiffness and resilience, and, while the sheet material is plastic and substantially wholly free of stiffness and resilience, applying it to adjoining box elements 35 in embrace of their edges in adhesive attachment thereto.

ERNEST G. RIDER.
